**SIDE SWING CARRIAGE FOR LOADERS
AND THE LIKE**
Le Grand H. Lull, 5501 Woodlawn Blvd.,
Minneapolis, Minn.
Filed Nov. 8, 1961, Ser. No. 151,004
8 Claims. (Cl. 214—147)

This invention relates to a new and improved machine for loading, unloading, transporting and placing articles; in particular, it concerns a mobile load carrying machine having a pivotal side swing carriage adapted to handle and transport heavy elongated loads such as logs, poles, piping, tree-length logs and the like with a minimum of effort and with greater efficiency than heretofore possible.

A problem encountered in loading, lifting and carrying long logs, poles and the like is the severe limitation placed upon conventional equipment with regard to maneuverability and operational ease when such articles are carried with their long axis transverse to the direction of travel. For example, a 95 foot utility pole, when carried by a conventional fork truck, requires at least as much clearance as its length indicates to pass from one location to another. For this reason, such articles are generally handled by power cranes and derricks at a cost greatly in excess of the normal amount necessary to handle loads of similar weight but with substantially less length.

Furthermore, when a conventional fork truck or loader is used for this purpose, it must approach the load at a direction perpendicular to the axis of the load and then back away and turn in the desired direction with due regard to the extension of the load on each side of the machine. This characteristic is undesirable from an operational as well as a cost standpoint as additional labor and fuel are required to do the job, to say nothing of the extra space required. Generally, working areas for such articles lack the space necessary to transport them in a cross-wise manner.

Another shortcoming found in machines generally designed to handle logs, poles, structural steel and other elongated articles is the inability of their load engaging devices to accommodate themselves to payloads of varying diameters and cross-sectional shapes without extensive on-the-spot changing of the components of the machine. Also to be considered is the advantage of providing a single machine with removable and changeable load engaging members to increase its versatility and flexibility.

Accordingly, it is an important object of this invention to provide a machine that will overcome the above disadvantages and limitations.

Another primary object of this invention is to provide an improved machine for handling articles or bulk loads.

Another object of this invention is to provide a side swing carriage for loaders and the like.

Yet another object of this invention is to provide novel and improved means for facilitating the handling of large, unwieldy payloads characterized by great weight and length.

Still another object of this invention is to provide in a side swing carriage for loaders and the like novel and

2

improved means for accommodating the load engaging members of the carriage to loads of different size and character.

A further object of this invention is to provide a novel set of removable interchangeable lift arms or forks for a load engaging carriage.

Another object of this invention is to provide in a side swing carriage for loaders and the like novel and improved means for transmitting forces to the load engaging members.

Another object is to provide in a side swing carriage novel and improved means for transferring forces from an inner fixed frame to an outer movable frame.

Another object of this invention is to provide a side swing carriage for loaders and the like characterized by novel structural and functional features adapted to facilitate the easy handling of loads from the side of the machine to which the carriage is applied.

Yet another object of this invention is to provide a mobile load handling machine adapted to carry elongated payloads down an aisle or in a roadway of a width not greatly in excess of the width of the machine itself.

A further object of this invention is to provide a novel and improved side swing carriage for a load handling machine capable of lifting, carrying and handling logs, poles, culverts and other articles of similar length and weight.

A still further object of this invention is to provide in a side swing carriage of the type described novel holdown clamps capable of engaging and holding articles of varying size, shape and weight.

A further object of this invention is to provide a novel and improved hydraulically actuated carriage for loaders and the like adapted to carry poles, logs and like articles in more than one plane and almost parallel to the longitudinal axis of the machine to which said carriage is attached.

A further object of this invention is to provide a novel and improved hydraulically actuated carriage for loader and the like adapted to tilt logs and similar articles backward in a vertical plane almost 90° and forward in a vertical plane almost 45°.

Another object of this invention is to provide a side swing carriage structure for loaders and the like that can be manufactured from readily available material with a minimum of cost.

Another object of this invention is to provide a side swing carriage for loaders and the like having a compact and attractive appearance.

A further object of this invention is to provide a side swing carriage mechanism that is adaptable for manufacture of a simple model or toy simulating a mobile loader and using a minimum of parts.

A further object of this invention is to provide a side swing carriage for loaders and the like that can be mounted for either right or left hand operation.

These and other objects and advantages of the invention will become more fully apparent from a consideration of the following detailed description taken in conjunction with the accompanying drawings wherein a preferred embodiment of the invention is shown by way of illustration and not by way of limitation.

In the drawings:

FIGURE 1 is a side elevation view of a mobile loader swing my side swing carriage in two positions, the said position being indicated in dotted lines;

FIGURE 2 is a fragmentary top plan view of the forward end of a mobile loader with my side swing carriage shown in two positions, the solid lines indicating the carriage in a pivoted position, the dotted lines indicating the carriage in a straight non-pivoted position;

FIGURE 3 is a front elevational view of my side swing carriage;

FIGURE 4 is a perspective view of a mobile loader equipped with my side swing carriage showing the loader in a transport position;

FIGURE 5 is an enlarged fragmentary elevational view, partially in section, taken on the line 5—5 of FIGURE 3;

FIGURE 6 is an enlarged fragmentary elevational view, partially in section, taken on the line 6—6 of FIGURE 3;

FIGURE 7 is a perspective view of my side swing carriage;

FIGURE 8 is an enlarged fragmentary elevational view, taken on the line 8—8 of FIGURE 11;

FIGURE 9 is an enlarged fragmentary elevational view, partially in section, taken on the line 9—9 of FIGURE 3;

FIGURE 10 is an enlarged fragmentary view, partially section, taken on the line 10—10 of FIGURE 11;

FIGURE 11 is an enlarged fragmentary side view, with parts broken away, of the load engaging and support members forming part of my invention;

FIGURE 12 is an enlarged fragmentary top plan view, taken along the line 12—12 of FIGURE 9; and

FIGURE 13 is an enlarged fragmentary view, partially in section and with parts broken away, taken on the line 13—13 of FIGURE 7, showing the details of the tension bar connection forming part of my invention.

Referring now to the drawings, the invention, designed in its entirety by the reference character A, is shown mounted upon the forward end of a boom B that is rotatably mounted adjacent one end thereof on mobile loader C and extending longitudinally therefrom. Boom B which swings about a rear pivot axis in a vertical plane, is equipped with suitable hydraulic means 10 for raising and lowering and is further provided with a forwardly extending hydraulic jack 12 that is centrally carried between the boom members 14, 16. For maximum operational efficiency, boom B is preferably of the telescoping reaching type, although a longitudinally fixed boom may be used. Conventional means are provided for supplying fluid under pressure to the hydraulic elements hereinafter referred to.

As shown in FIGURES 3 and 7, my side swing carriage includes a laterally fixed inner frame 20 made up of a pair of horizontal spaced parallel tubular upper and lower structural members 22 connected by a pair of vertical structural members 23 and 24. At one end of frame 20 on the right hand side of the machine looking forward from the cab (not shown) a hollow vertical pivot member 26 is connected to members 22 to form therewith and with members 23 and 24 a laterally immobile centrally open inner support structure of great strength and rigidity.

Inner frame 20 is connected to the free end of boom B by means of the pivotal elements shown in detail in FIGURE 5. As illustrated, the rear surfaces of lower horizontal member 22 and vertical members 23, 24 are equipped with pivot brackets 28 suitably trunnioned upon lower free end 30 of boom B to provide for rocking movement of frame 20 about a pivot axis 31 disposed inversely of and adjacent the free end 30 of boom B. Hydraulic jack 12, located centrally and longitudinally on boom B, is connected at its rearward end to suitable supporting structure (not shown) within boom B and at its forward end to a pintle 32 carried by spaced parallel vertical braces 34 mounted centrally between members 23 and 24 and connected to members 22. This arrangement permits the selective rocking of inner frame 20 of swing

carriage A about a transverse pivot axis 31 adjacent the free end 30 of boom B.

FIGURES 3, 6 and 7 show the details of the supporting structure provided for mounting the inner end of hydraulic jack 50 to inner frame 20, the outer end of which is secured, as will be explained, to outer frame 42 to impart swinging movements thereto. A solid upwardly extending plate 52 is welded, or otherwise suitably secured, to the rear of upper member 22 and post 24. Suitable diagonal bracing members 54, 55 are so arranged as not to interfere with the structural elements of outer frame 42 (shown in dotted lines in FIGURE 6) when outer frame 42 is swung into a closed and nested position with respect to inner frame 20. Stiffener 56 at the rear of plate 52 provides extra strength and rigidity. A pair of horizontal parallel vertically spaced forwardly extending brackets 58 are carried by the upper end of plate 52 adjacent upper brace 55, into which is mounted a vertical fixed pin 60, to which is secured one end of hydraulic jack 50. As shown in FIGURE 6, the axis of pin 60 coincides generally with the vertical axis of frame member 24 of inner frame 20.

Turning now to a description of outer swingable frame 42, this structure includes a pair of horizontally spaced tubular vertical end posts 62, 64, which are connected by a pair of tubular upper and lower horizontal members 66 and 68, respectively. The inner spatial limit of the centrally open rectangular form resulting from the arrangement of posts 62, 64 and members 66, 68 is of such a length and width as to surround in closely spaced relation the corresponding outer spatial limit of inner frame 20 so that outer frame 42 may assume a nested lateral position with respect to inner frame 20, as shown in FIGURES 1, 3 and 7.

FIGURES 3, 7 and 9 illustrate the pivotal connection joining inner frame 20 and outer frame 42. Carried within pivot member 26 of inner frame 20 are a pair of hollow bearing plugs 38 located adjacent each end thereof. Rotatably mounted within pivot member 26 and supported by plugs 38 is a solid cylindrical pivot shaft 40 which extends beyond each end of pivot member 26. Adjacent the inner end of horizontal members 66, 68 of outer frame 42 are a pair of hollow vertical sleeves 70, 72, mounted in members 66 and 68, respectively. Sleeves 70 and 72 are in alignment with each other and with the axis of pivot member 26 and shaft 40 so as to receive shaft 40 therein. FIGURE 9 illustrates sleeve 70; sleeve 72 (not shown) is identical therewith but is located in member 68. Adjacent the lower end of sleeve 70 and hollow circular boss 74 is welded. A bearing surface between pivot member 26 of inner frame 20 and member 66 of outer frame 42 is provided by a hollow circular bronze bushing 75 mounted on shaft 40 therebetween. A collar 76 on each end of shaft 40, suitably attached thereto by means of diametral bolt 78, prevents the axial displacement of shaft 40 and holds the pivotal assembly in place. A hollow circular spacer 79 on shaft 40 between the lower end of pivot member 26 and member 68 takes up the slack in the assembly. Thus outer frame 42 pivots with respect to inner frame 20 about a pivot axis 81 (see FIGURES 2, 3 and 7) defined by the axis of shaft 40 and pivot member 26.

Located intermediate the aforementioned pivot axis and the free end of member 66 is a forwardly extending horizontal support 80 upon which is mounted, in forwardly and upwardly spaced relation to member 66, a vertical pin 82 adapted to receive the outer end of hydraulic jack 50.

End posts 62 and 64 each carry adjacent their upper ends two pairs of fixed spaced forwardly extending ears 84, 86 having suitable apertures therein to receive bearing pins 88, 90, 92 and 94. Upper ears 84 are adapted to receive pins 88 and 90 with the axes thereof in vertical register, while lower ears 86 receive pins 92 and 94, which also have their axes in a common horizontal plane spaced vertically below and parallel to the axes of pins 88 and 90. Rotatably secured to pins 88 and 90, respectively, are

a pair of horizontally spaced upper crank members 96 and 98. Similarly, a pair of lower crank members 100 and 102 are pivotally secured to lower pins 92 and 94. As shown in FIGURE 1, the axes of pins 88 and 92 are in horizontal register. Crank members 96, 98, 100 and 102 are practically identical in construction, each including a pair of spaced parallel elongated side panels 104, 106 suitably reinforced intermediate their ends by a central stiffener consisting of plates 108 that are welded at each end thereof to transverse solid cylindrical members 110, as shown in FIGURES 3 and 7.

Carried at the outer end of each of the crank members 96, 98, 100 and 102 are a pair of spaced load bearing vertical link members 112 and 114. Link members 112 and 114 are identical to each other, each being characterized by a pair of generally elongated side plates 116 having a generally horizontal lower edge 118 and gradually tapering sides 120 that terminate in a narrow top surface 122. Suitable central reinforcing 123 is provided between the side plates 116. Adjacent the top 122 of link members 112 and 114 bearing pins 124, 126 are carried, upon which are mounted the forward ends of upper crank members 96 and 98, respectively. Bearing pins 128 and 130 are similarly mounted between the side plates 116 of link members 112 and 114 in spaced relation below pins 124 and 126 to receive lower crank members 100 and 102, respectively. This construction results in a four bar linkage consisting of upper crank members 96, 98, lower crank members 100, 102, link members 112, 114 and the fixed supports resulting from the attachment of the crank members to posts 62 and 64 of outer frame 42.

The lower ends of link members 112 and 114 are provided with hold-down clamps 130 and 132, respectively. Each hold-down clamp 130, 132 is characterized by an elongated load engaging member 134 and a central upstanding rib 136 extending upwardly therefrom into engagement with link members 112, 114. The contour of the undersurface of member 134 (FIGURES 7 and 11) is sharply concave downwardly, as at 138, near the forward end thereof and slightly concave upwardly, as at 140, adjacent the rear tip thereof. Between these points member 134 is substantially flat. Mounting of clamp 130 within link member 112 is accomplished by positioning rib 136 between the side plates 116 of link member 112. Suitable filler plates 117 accommodate the connection. As shown in FIGURE 10, a pair of longitudinally spaced vertical slots 140', 142 are located in rib 136 of clamps 130, 132 into which extend bearing pins 144, which are carried by the lower ends of link members 112 and 114, to allow vertical displacement of clamps 130, 132 thereabout. The dotted line position of clamp 130 in FIGURE 11 is illustrative of this characteristic of the invention.

Further provided upon outer frame 42 are a pair of laterally spaced lift arms or forks 146 and 148 extending forwardly from posts 62 and 64, respectively. Lift arms 146 and 148, each removably attached to outer frame 42, are characterized by a rear vertical leg 150 and a forwardly extending generally horizontal leg 152 which is positioned in register with the lower surface of posts 62 and 64. Connection between the rear vertical legs 150 of lift arms 146, 148 and posts 62, 64 is made by a pair of spaced upper side plates 154 attached to each leg 150. Brackets 154 have opposed downwardly open notches 156 engageable with cylindrical bosses 158 that are welded into diametrically opposite sides of posts 62 and 64 to form horizontal laterally extending supports for side plates 154. As shown in FIGURES 7 and 8, the lower rear ends of lift arms 146 and 148 are removably attached to frame 42 by a pair of parallel spaced depending brackets 160 secured to the lower end of the undersurface of lower horizontal member 68 beneath posts 62 and 64. Brackets 160 receive rearwardly extending lugs 162 secured to the lower rear surface of legs 150 of lift arms 146 and 148. Lugs 162 and brackets 160 are provided with a common aperture 164 into which is placed a removable pin 166 adapted to releasably hold the assembly together.

Means for actuating hold-down clamps 130 and 132 consists of a pair of hydraulic jacks 170 and 172 attached at one end thereof to bearing pins 88 and 90, respectively and at the opposite end thereof to pins 128 and 130, respectively. It can be seen that a considerable mechanical advantage can be obtained by virtue of the jacks 170, 172 and their positioning with respect to the linkage member 100, 102 and pins 88 and 90. That is to say, the diagonally forward positioning of jacks 170, 172 within each of the laterally opposed crank members 100, 102, in combination with the hydraulic power obtained in the jacks themselves, results in a multiplication of force adequate to rigidly clamp logs, culverts, structural products, piping and the like, between hold-down clamps 130, 132 and lift arm 146 and 148.

To take up any lateral or diagonal twisting moment that may occur during periods of peak load usage, I have provided a lateral torsion bar 176 that extends between lower crank members 102 in the manner shown in FIGURES 3, 7 and 13. This feature consists of a pair of slotted cylindrical brackets 178 that are positioned on the inner side plates 104 of lower crank members 102 in horizontal alignment with each other. A slender elongated torsion rod 180 having an open eye 182 formed in each end is secured within brackets 178 by suitable bolted or pin connections 184. Torsion bar 176 keeps the hold-down clamps 130, 132 in reasonable alignment during no-load conditions; when the carriage is loaded, torsion bar 176 restricts the separation of clamps 130, 132 within the limits defined by the length of the eyes 182 at each end thereof. Further provided for stiffening outer frame 42 is a diagonal sway brace 186.

Operation and use of the device

The features above described offer unique advantages for the loading and transporting of articles, particularly items such as utility poles, structural beams and columns, culverts, piping and tubing, logs, lumber, and other elongated members which are relatively difficult to handle because of their length and weight.

For example, when loading a utility pole, the operator may approach a pile of poles in a straight forward position, as indicated by the dotted lines of FIGURE 2, then back away and rotate carriage A about pivot axis 81 so that the log D may be carried roughly parallel to the line of travel of the machine (indicated by the solid lines of FIGURE 2). By positioning the log D between the outer end of the outside clamping members (indicated by reference character 190 in FIGURE 2) and the inner end of the inside clamping members (as at 192 in FIGURE 2), a maximum degree of parallelism of the log D with the longitudinal axis of the machine can be obtained. The centrally open construction of inner frame 20 and outer frame 42 also provides for maximum visibility for the operator at all times regardless of the position of the boom and its load. As shown in FIGURE 4, by swinging carriage A to a side position, poles and other elongated load can be transported along roadways and narrow aisles of width not greatly in excess of the width of the machine. Loads can also be placed upon carriage A when it is swung into a side position, the exact technique used depending upon the circumstances encountered in an individual case. It has been found that long poles, trees, piping, and the like are easier to carry if the load is placed within outer frame 42 so that its center of gravity is well forward of the machine to offset any unbalance caused by the weight of the load as it is swung to one side.

The strength built into the outer frame 42, by virtue of the unique arrangement of the upper and lower crank members 96, 98, 100, 102 and the link members 112, 114 with its connection to the hold-down clamps 130, 132, enables the structure to securely hold exceptionally long and unwieldy poles and other articles of similar length and weight for safe transport, placing and angling. By providing suitable lifting characteristics for the boom 1 a versatility hitherto unknown can be achieved. Mobil-

machines of the type disclosed herein have satisfactorily ed, transported and set down utility poles 95' in length h ease and facility. By elevating boom B and swing-; carriage A to its extreme side and forward position, og of such length can be positioned almost perpendicular to the ground by swinging it backward in a vertical ne almost 90°; when carriage A is swung forward dur-; the time boom B is raised to its upper limit a log of sh length can be swung forward in a vertical plane ast 45°. For such loads and conditions, however, it advisable to use my carriage A on mobile machines of proper design and construction bearing in mind the tribution of the several forces encountered with such a d.

The features described in connection with the hold-wn clamps 130, 132 and the manner in which they are ried by link members 112, 114 allow for the accom-modation of varying diameter logs, poles, etc. between arms or forks 146, 148 and clamps 130, 132. The otting of clamps 130, 132 in a plane perpendicular to load members permits the facile and safe clamping gagement of the hydraulically operated clamping struc-e about logs, poles, structural shapes, piping and the e. In the case of metal piping, tubing, structural steel other loads characterized by smooth non-resilient in-sible surfaces, the inner clamping surfaces of hold-down mps 130, 132 and/or lift arms 146, 148 may be ipped with suitable resilient material adapted to yield-ly engage and firmly hold the payload. Conventional ans, such as bonding or rivetting, may be used to secure h material to the inner clamping surfaces of the hold-down clamps and the lift arms to provide additional safety 1 workability to the carriage.

When a particularly long and heavy load is contem- 5 pted for carrying, lift arms or works 146, 148 must be sufficient strength to withstand not only the payload t also the forces imposed by the operation of the hy- 10 dular jacks upon the clamping members 130, 132. For iling lighter loads it may be feasible to use lift arms forks of lighter weight and cross section; therefore, I ve shown novel and improved means for removably 15 mounting lift arms 146, 148 upon the outer frame 42 to ease the versatility of the device, without substantially 20 affecting its overall cost.

My invention has been sufficiently tested and found to entirely satisfactory. It will be obvious to those skilled the art that my invention may be modified by many stitutions and equivalents and that this disclosure is ended to be illustrative only. In the claims when the ms "horizontal" or "vertical" are referred to, the orientation described is to be taken as meaning a vertical or horizontal orientation when the machine is in a normal el position with the forwardly extending legs of the arms or forks of the carriage in a horizontal position. h language is not intended to limit or narrow the pe of the claims in any sense. Furthermore, it may possible to use my novel swing carriage on scale model s and other unconventional environments where its tures may be found useful. It is within the purview this invention to encompass such uses and I intend to limited solely by the scope of the appended claims. 25 claim:

.. In a load carrying machine, a mobile body, a ver- 30 ally swingable boom rockably mounted adjacent one l thereof on said mobile body and extending therefrom, a laterally fixed frame mounted for vertical rocking vement on said boom about a horizontal pivot axis osed transversely of and adjacent the free end of said m, actuating means connected to said frame and op- 35 able to effect relative vertical pivotal movement of said ne with respect to said boom, a laterally swingable d-engaging frame carried by said fixed frame and 40 mounted for horizontal rocking movement on said fixed ne about a vertical pivot axis adjacent an outer end said fixed frame, said vertical pivot axis being perpen- 45

dicular to said first mentioned transverse pivot axis, ac- 5 tuating means connected to said swingable frame and to said fixed frame and operable to effect relative lateral 10 swinging movements of said swingable frame with respect to said fixed frame, a pair of laterally spaced forwardly 15 extending lift arms carried by said swingable frame at the lower ends thereof, a pair of laterally spaced upper crank members each mounted for vertical rocking movement on said swingable frame about a horizontal pivot axis ad- 20 jacent the top of said swingable frame, a pair of laterally spaced lower crank members mounted for vertical rock- 25 ing movement on said swingable frame about a horizontal pivot axis below said last mentioned pivot axis, a pair of laterally spaced vertical link members each pivotally connecting an upper and a lower crank member and extending 30 therebelow, a hold-down clamp carried by the free end of each of said link members over said lift arms, and actuating means connected to said swingable frame and operable to effect releasable clamping engagement of arti- 35 cles carried between said hold-down clamps and said lift arms.

2. The structure defined in claim 1 wherein said last mentioned actuating means consists of a pair of hydraulic jacks each connected at one end thereof to said swingable 40 frame adjacent the top thereof and connected at the other end thereof to said lower crank members adjacent said link members.

3. The structure defined in claim 1 wherein said hold- 45 down clamps are toggle mounted to said link members to effect limited vertical pivotal movement of said hold-down clamps about closely spaced horizontal axes perpendicular to and intermediate the length of said hold-down clamps.

4. The structure defined in claim 1 wherein said lift 50 arms are removably attached to said movable frame.

5. The structure of claim 1 wherein a torsion member connects said lower crank members.

6. In a carriage for loaders of the type having a for- 55 wardly extending boom, a load engaging frame carried by the front end of said boom, at least two laterally spaced forwardly extending lift arms mounted on said frame, upper and lower crank members pivotally carried by said frame above each of said lift arms, vertical link members pivotally connected to each of said upper and lower crank members and extending therebelow, a hold down clamp carried by the lower end of said link members above said lift arms, and hydraulic means connected to said frame and to said lower crank members operable to effect clamping engagement of articles carried between said hold down clamps and said lift arms.

7. In a loader, including a front end load-engaging 60 structure having laterally spaced generally vertical lift arm support members, a generally horizontal support member connecting the lower end of said vertical support members, the combination with said support members of laterally extending generally horizontal support bosses on each side of said vertical support members in spaced relation above said horizontal support member, bracket means extending below said horizontal support member in register with said vertical support members, a forwardly 65 extending lift arm removably attachable to each of said vertical support members and to said bracket means, said lift arm including a rear vertical leg, lug means adjacent the lower end of said rear vertical leg removably engageable with said bracket means, and a pair of side plates se- 70 cured to the top of said rear vertical leg, said side plates bearing against opposite sides of said vertical support members and having opposed notched out portions adapted to rest upon said support bosses.

8. In a loader for handling logs, poles, piping and 75 similar heavy elongated loads, including a mobile frame, a forwardly extending boom carried by said frame, laterally fixed support structure carried at the front end of said boom, the combination comprising: a hollow vertical pivot members forming one side of said support member,

a pivot shaft carried within and extending above and below said pivot member,
 a load engaging frame pivotally mounted on the upper and lower extensions of said pivot shaft for side swinging movements with respect to said frame,
 5 hydraulic cylinder means for swinging said load engaging frame from a forward position to a side position,
 a pair of forwardly extending lift arms, and
 a pair of hold down clamps pivotally mounted on said load engaging frame above said lift arms for clamping movement generally parallel to said lift arms.
